VARIABLE PITCH PROPELLER

Walter W. Everts, Baltimore, Md., assignor to
Everel Propeller Corporation, Baltimore, Md., a
corporation of Maryland

Application March 11, 1939, Serial No. 261,323

6 Claims. (CL 170—164)

My invention relates to propellers for air craft, boats, submarines, or the like.

An important object of the invention is to provide a propeller having a blade which is so pivotally mounted that the pitch of the blade is increased by the action of centrifugal force and this action is opposed by the action of the fluid medium in which the blade is rotating, whereby the pitch of the blade automatically increases when the pressure of the fluid medium decreases and the speed of rotation of the blade will remain substantially constant.

A further object of the invention is to provide means for mounting a non-metallic blade, such as a wooden blade, upon an attaching element, in such a manner as to prevent the creeping of the blade upon the attaching element, against centrifugal force stresses.

A further object of the invention is to provide a laminated wooden propeller, having the maximum tensile strength in that portion of the blade which receives the anchor element of the connecting unit.

A further object of the invention is to provide means for affording the maximum binding strength between the anchor element and the blade against the pulling action of centrifugal force.

A further object of the invention is to provide coupling units for securely receiving and holding the connecting elements, and which coupling units are pivotally mounted upon the rotary element or hub.

A further object of the invention is to provide means whereby the central longitudinal axes of the blades are arranged at an inclined angle with respect to the axes of the pins upon which the couplings turn.

A further object of the invention is to provide a damping device for connecting the blades, to cause them to move as a unit when one blade is suddenly subjected to force, and subsequently allowing the blades to move separately, to vary their pitch.

Other objects and advantages of the invention will be apparent during the course of the following description:

In the accompanying drawings forming a part of this application and in which like numerals are employed to designate like parts throughout the same,

Figure 1 is a front elevation of a propeller embodying my invention, viewed from the front of the airplane,

Figure 2 is an edge elevation of the same,

Figure 3 is a perspective view of the connecting element,

Figure 4 is a central longitudinal section through the connecting element and associated elements,

Figure 5 is a transverse section taken on line 5—5 of Figure 1,

Figure 6 is a longitudinal section taken on line 6—6 of Figure 2,

Figure 7 is a vertical section taken on line 7—7 of Figure 1,

Figure 8 is a similar view taken on line 8—8 of Figure 1,

Figure 9 is a similar view taken on line 9—9 of Figure 1.

In the drawings, wherein for the purpose of illustration is shown a preferred embodiment of my invention, the numeral 10 designates the crank shaft of an internal combustion engine, 20 mounted upon an airplane or the like. Keyed to this shaft 10 for rotation therewith is a hub 11, held against longitudinal displacement by a nut 12, as shown. The hub 11, see particularly Figure 6, has oppositely arranged radial pivot elements or pins 13, preferably tubular.

The numeral 14 designates a pair of companion coupling members or yokes. Each of these coupling members or yokes is formed in 30 companion sections 15 and 15', having flat inner contacting faces 16. The companion sections are secured together by bolts 17 or the like. Each coupling member or yoke 14 has a bearing sleeve 18 at one end and a bearing sleeve 19 at its opposite end. These bearing sleeves receive

35 bronze bushings 20 and 21, respectively. These bronze bushings are floating. As clearly shown in Figure 6, the sleeves 18 and 19 of the companion yokes are arranged in end-to-end relation, the sleeve 18 of one yoke being disposed 40 outwardly of the sleeve 19 of the companion yoke. Each sleeve 19 has a raceway for receiving radial ball bearings 21, engaging the bushing 20, and each pin or pivot element 13 carries an end thrust ball bearing 22, arranged between

45 the shoulder 23 and the shoulder 24 of the sleeve 19. It is thus seen that the coupling members or yokes are pivotally mounted upon the pivot elements or pins 13, to turn thereon, but are securely held against radial displacement with 50 relation thereto. Attention is also called to the fact that the coupling members or yokes 14 extend radially beyond the hub 11 and its axis of rotation and the longitudinal axes 25 of the radially extending portions are disposed upon opposite sides of the hub, as shown.

55

The numeral 26 designates connecting elements as a whole, for securing the blades to the coupling members or yokes 14. Each connecting element comprises a shank 27, which is preferably hollow, as shown in Figure 4. The shank has a flange 28, as shown. The shank is preferably circular in cross-section and is inserted in a socket 29, formed in the outer end of each coupling member or yoke 14, and the flange 28 is held within an annular groove 30. The shank is clamped in the socket 29 against turning movement. Particular attention is called to the fact that the socket 29 and the shank 26 held therein has its longitudinal axis arranged at an inclined or oblique angle with relation to the longitudinal axis of the adjacent pin 13. Each connecting element includes a flat anchor element 31, formed integral therewith. This flat anchor element is generally heart-shaped and tapers radially outwardly and has shoulders 32, at its inner end. The opposite sides of the flat anchor element 31 at their inner ends, are also connected with the shank 26 by tapered webs 33.

The numeral 34 designates blades, preferably formed of wood. These blades are cut to produce the desired pitch. These blades are of the conventional shape, having the leading faces convex or cambered. As stated, the longitudinal axes of the shanks 27 are arranged at an oblique angle with respect to the longitudinal axes of the pins 13, and satisfactory results are obtained by having the axes of the shanks 27 disposed at an angle of about 25 degrees with respect to the longitudinal axes of the pins 13. It is preferred that the leading and trailing portions 35 and 36 of each propeller should be unbalanced with the trailing area larger.

As stated, the propeller blades are preferably formed of wood, and each blade comprises an inner flat section 37, formed of a number of relatively thin layers or laminations of wood, glued together. This section is preferably built up as a unit separate from the remaining sections. The propeller comprises outer sections 38, formed of layers or strips 39 and 40, glued together. Each outer section is also preferably first formed as a unit. The inner laminated section 37 formed of the relatively thin strips has the same thickness as the flat anchor element 31, and a recess 41 is cut in this inner laminated section 37, corresponding in shape and size to the anchor element 31 and the shank 27. The outer sections 38 of the propeller have inner recesses 42 formed therein, to receive portions of the shank 27 and the webs 33. The anchor element 31 has a relatively large central opening 43, to receive a wooden slit plug 44, having the same thickness as the flat anchor element 31. The anchor element 31 also has transverse openings 45, arranged in a triangular group to receive metal pins or plugs 46, having a driving fit therein, and these pins or plugs also pass through openings 47 formed in the outer sections 38. In securing the connecting element with the propeller blade, one section 38 is arranged lowermost and the inner laminated section 37 arranged thereon and the anchor element 31 is then placed within the opening 41 of the inner laminated section 37. The upper section 38 is now placed upon the intermediate laminated section 37, these parts being so arranged that the openings 47 and 45 register. The wooden plug 44 has also been placed within the opening 43. The inner contacting surfaces of the sections 38 and the laminated section 37 and the plug are suitably coated with glue and the thus assembled

sections are then subjected to suitable pressure and maintained under this pressure until the glue has properly dried. The assembled sections are in the form of a rectangular block and after the sections have become properly glued together and dried the outer sections are then properly cut so that they produce the propeller blade of the desired shape. The pins 46 are finally driven into the openings 45. I have found that I have thus obtained a connection between the shank 27 and the blade which will securely hold the blade upon the shank so that the blade will not creep, due to radial thrust. This is important as it is well known that one of the disadvantages encountered in the use of the ordinary adjustable wooden propeller is that the inner ends of the blades creep slightly in the metal sockets within which they are mounted, which causes the propeller to become unbalanced.

20 The coupling members or yokes 14 are interconnected by damping devices, arranged upon the leading side of the yokes. Each damping device comprises a cylinder 49 having its opposite ends provided with packing 50 and 51, forming a gas-tight joint with a plunger rod 52. This plunger rod carries a plunger 53, having a contracted port 54. The cylinder 49 may be filled with air or with a liquid, if desired. A tube 55 is attached to the lower end of the cylinder 49 and this tube is pivotally connected with a pin 56 which in turn is secured to the lower yoke 14 near its inner end. The plunger rod 52 is pivotally connected with a pin 57, which is secured to the upper or companion yoke 14, near its outer end. The function of these damping devices is to cause the blades to move as a unit, when one blade is suddenly subjected to force or pressure, and subsequently permitting the blades to move separately to vary their pitch.

40 The operation of the propeller is as follows:

When the engine is started, the propeller is turned counterclockwise, viewed from the front of the airplane, which is the practice in the United States. As soon as the propeller rotates centrifugal force acting upon each blade 34 tends to move the same to the radial position. This action of centrifugal force is opposed by the air thrust, which tends to swing each blade upon the pivot 13 so that the outer end of the blade moves forwardly from the radial position. These two opposing forces act against each other and the blade will assume a normal operating position between the extreme forward position and the true radial position. Assuming the airplane is now flying at substantially sea level, the air thrust is at the maximum and the blade has its outer end moved forward slightly from the radial position, so that the blade will have the minimum pitch. When the blade is turned upon its diagonal pivot 13, this pivot being diagonal with respect to the central longitudinal axis 35' of the blade, it is also turned upon its longitudinal axis 35, thereby varying the pitch of the blade. The unbalanced areas 35 and 36 also aid in turning the blade about its longitudinal axis 35'. When the blade turns upon the diagonal pivot 13 the longitudinal axis 35' of the blade swings about the surface of a cone. The action of centrifugal force tends to move the blade upon its pivot 13 to the true radial position, thereby increasing the pitch of the blade. Assuming that the propeller is being driven 2000 R. P. M. at sea level, the propeller will then have the minimum pitch for this elevation. If the airplane now rises to a considerably higher elevation, the resistance acting

upon the propeller will be reduced, while the action of centrifugal force would remain the same and hence the action of centrifugal force would overcome the air thrust upon the propeller blade and the propeller blade would be turned upon its diagonal pivot 13 in a rearward direction, turning the blade about its longitudinal axis for increasing the pitch of the propeller. This increased pitch of the propeller will cause the propeller to drive the airplane at an increased speed but the speed of rotation of the propeller will remain constant.

Having thus described my invention, what I claim is:

1. In a variable pitch propeller construction provided with propeller blades, a rotary member, a pivotal member fixed to and extending radially from the rotary member, a pair of yokes journaled on the pivotal member, said yokes being offset from each other and extending radially beyond the pivotal member, a damping device connecting the said yokes, a recess in the outer portion of each yoke, the longitudinal axis of said recess being at an inclined angle with relation to the longitudinal axis of the pivotal member, and a shank mounted in each recess, each shank connecting the yoke in which it is mounted to a blade of the propeller.

2. In a variable pitch propeller construction provided with propeller blades, a rotary member, a pivotal member fixed to and extending radially from the rotary member, a pair of yokes journaled on the pivotal member, said yokes being offset from one another and extending radially beyond the pivotal member, a damping device connecting the said yokes, a recess in the outer portion of each yoke, the longitudinal axis of said recess being at an inclined angle with relation to the longitudinal axis of the pivotal member, a shank mounted in each recess, each shank connecting a yoke with a blade of the propeller, the axis of each shank extending longitudinally in respect to the longitudinal axis of the recess in which it is mounted, each of said shanks comprising a root portion adapted to be carried within the recess and an outer portion designed to be attached to the blade.

3. In a variable pitch propeller construction provided with propeller blades, a rotary member, a pivotal member fixed to and extending radially from the rotary member, a pair of yokes journaled on the pivotal member, said yokes being offset from one another and extending radially beyond the pivotal member, a damping device connecting the said yokes, a shouldered recess in the outer portion of each yoke, the longitudinal axis of said recess being at an inclined angle of 25 per cent with relation to the longitudinal axis of the pivotal member, a shank mounted in each recess, each shank connecting the yoke in which it is mounted with a blade of the propeller, the axis of each shank extending longitudinally in respect to the axis of the recess in which it is mounted, each of said shanks comprising a root portion adapted to be carried within the recess and provided with a flanged portion which engages the shoulder of the recess, and an outer portion designed to be attached to the blade.

4. In a variable pitch propeller construction provided with propeller blades, a rotary member, a pivotal member fixed to and extending radially from the rotary member, a pair of yokes journaled on the pivotal member, said yokes being in end to end relation and offset from one another and extending radially beyond the piv-

otal member, a damping device connecting the said yokes, each of said yokes comprising a pair of contacting faces secured together, a shouldered recess in the outer portion of each yoke, the longitudinal axis of said recess being at an inclined angle with relation to the longitudinal axis of the pivotal member, a shank mounted in each recess, each shank connecting the yoke in which it is mounted with a blade of the propeller, the axis of each shank extending longitudinally in respect to the axis of the recess in which it is mounted, each of said shanks comprising a root portion adapted to be carried within the recess, a flanged portion on each root portion designed to engage the shoulder of the recess, and an outer portion designed to be attached to the blade.

5. In a variable pitch propeller construction provided with propeller blades, a rotary member, a pivotal member fixed to and extending radially from the rotary member, said pivotal member comprising offset shafts, a pair of yokes in end to end relation and offset from one another and extending radially beyond the pivotal member, a damping device connecting the yokes, each of said yokes comprising a pair of contacting faces secured together and provided with a pair of sleeves in end to end relation which carry a bushing journaled on one of the shafts forming the pivotal member, whereby the yoke is rotatably mounted in respect to the shaft of the pivotal member, the outer sleeve of each yoke being positioned exteriorly in respect to the inner sleeve of the companion yoke, a recess in the outer portion of each yoke, the longitudinal axis of the recess being inclined at an angle with respect to the longitudinal axis of the pivotal member, a shank mounted in each recess, each shank connecting a yoke with a blade of the propeller and the axis of each shank extending longitudinally in respect to the longitudinal axis of the recess in which it is mounted, each of said shanks comprising a root portion adapted to be carried within the recess and an outer portion being designed to be attached to the blade.

6. In a variable pitch propeller construction provided with propeller blades, a rotary member, a pivotal member fixed to and extending radially from the rotary member, said pivotal member comprising offset shafts, and a shoulder on the inner extremity of each shaft, a pair of yokes in end to end relation and offset from one another and extending radially beyond the pivotal member, a damping device connecting the yokes, each of said yokes comprising a pair of contacting faces secured together and provided with a pair of sleeves in end to end relation which carry a floating bushing adapted to be journaled on one of the shafts forming the pivotal member, a ball bearing raceway in the inner sleeve, a shoulder in the inner sleeve, a bearing between the shoulder and the said shoulder on the shaft of the pivotal member, whereby the yoke is rotatably mounted in respect to the shaft of the pivotal member, the outer sleeve of each yoke being positioned exteriorly in respect to the inner sleeve of the companion yoke, a shouldered recess in the outer portion of each yoke, the longitudinal axis of the said recess being inclined at an angle with relation to the longitudinal axis of the pivotal member, a shank mounted in each recess, each shank connecting a yoke with a blade of the propeller, and the axis of each shank extending longitudinally in respect to the longitudinal axis of the recess in which it is mounted,

each of said shanks comprising a root portion adapted to be carried within the recess, a flanged portion on each root portion designed to engage the shoulder of the recess, and an outer portion being designed to be attached to the blade, said outer portion consisting of a flat plate member

defining a plurality of apertures, means extending through the apertures to connect the plate member to the blade, and a wedge-shaped web member connecting the root portion and the said plate.

WALTER W. EVERTS.
